CLAIM

I claim the ornamental design for a golfball lifter for a flagstick, as shown and described.

DESCRIPTION

FIG. 1 is a perspective view of golfball lifter for a flagstick showing my new design, the view for the opposite side being identical thereto;

FIG. 2 is a downward perspective view thereof, the view for the opposite side being identical thereto;

FIG. 3 is a top plan view thereof;

FIG. 4 is cross sectional view taken at line 4-4 of FIG. 3;

FIG. 5 is cross sectional view taken at line 5-5 of FIG. 3; and,

FIG. 6 is a bottom plan view thereof.

The cross sectional views are to aid in showing the structure in order to minimize the number of views. The broken tubular portion of FIGS. 1 and 2 is not part of the invention and illustrates that the length of the tubular portion is not part of the claim.

The tubular portion separated and bound by a bracket in FIGS. 1 and 2 is shown to indicate indeterminate length and forms no part of the claimed design.

1 Claim, 6 Drawing Sheets(56)
